UNITED STATES PATENT OFFICE.

FRANK N. CANULETTE, OF SLIDELL, LOUISIANA.

GRAPPLING-HOOK.

1,141,038.

Specification of Letters Patent. Patented May 25, 1915.

Application filed June 12, 1914. Serial No. 844,787.

To all whom it may concern:

Be it known that I, FRANK N. CANULETTE, a citizen of the United States, residing at the village of Slidell, in the parish of St. Tammany and State of Louisiana, have invented certain new and useful Improvements in Grappling-Hooks, of which the following is a specification.

This invention relates to grappling hooks.

10 The object of this invention is the provision of a grappling hook provided with slideable prongs adapted to be moved to and from the object to be lifted.

15 Another object of this invention is the provision of a grappling hook comprising a plurality of spaced supporting bars and means for slidably attaching grappling prongs to said supporting bars.

20 A further object of this invention is the provision of a grappling hook embodying a plurality of oppositely disposed grappling prongs and means for moving said prongs to and from each other.

25 A still further object of this invention is the provision of a device of the character described, which will be comparatively simple and inexpensive to manufacture, reliable and efficient in use, and readily operated.

30 With the above and other objects in view, this invention resides in the novel features of construction, formations, combinations, and arrangements of parts to be hereinafter more fully described, claimed and illustrated in the accompanying drawings, in which:

Figure 1 is a top plan view of my improved grappling hook. Fig. 2 is an end view thereof. Fig. 2^a is a fragmentary view 40 illustrating means for operating the grappling prongs. Fig. 3 is a fragmentary detail side elevation of one of the grappling prongs and the mounting therefor. Fig. 4 is a detail transverse sectional view taken 45 on the line x—x of Fig. 3.

Referring to the accompanying drawings by similar characters of reference throughout the several views, the numeral 5 denotes in general my improved grappling hook 50 which consists of the spaced parallel end bars 6 formed preferably from channel iron and connected by parallel outer supporting bars 7, and inner supporting bars 8. These supporting bars 7 and 8 are connected to the end bars 6 by the brackets 9, through which fastenings 11 are inserted for rigidly at-

taching said brackets 9 to the bars 6, 7 and 8.

A plurality of spaced parallel supplemental bars 12 extend between the before described end bars 6 and are arranged in pairs, as clearly shown in Figs. 1 and 2 of the drawings. The ends of these bars 12 are connected by the attaching plates 13 through which fasteners 14 are passed to 65 secure the said bars 13 rigidly to the upper horizontal flanges of the bars 6.

U-shaped slides 15 engage the under and side edges of the bars 7 and 8 and support the shanks 16 of the grappling prongs 17. 70 These grappling prongs 17 are provided with inwardly projecting terminals 18 designed to engage the article to be lifted. As clearly shown in the figures of the drawings these grappling prongs 17 are arranged 75 in confronting pairs and are slideable at one end of the grappling hook 5 upon the outer bars 7, and at the opposite end, upon the inner bars 8.

U-shaped bolts 19 surround the shank 16 80 of the prongs 17 and the bars 7 and 8, together with the sliding member 15, and pass through apertures formed in the opposite edges of the plates 20, to which they are connected by nuts or other suitable fastening devices, such as shown at 21. The prongs at the opposite ends of the grappling hook 5 are connected by the transverse rods 22 and 23, respectively, and to these rods 22 and 23 are connected the inwardly 90 extending flexible cables 24 and outwardly extending flexible cables 25. The cables 24 pass over the inner pulleys 26 journaled between the before-described supplemental bars 12, while the cables 25 pass over the 95 outer pulleys 27 which are mounted in brackets 28 secured, as clearly shown in Figs. 1 and 2, within the channels of the end bars 6. The pulleys 26 and 27 are positioned and arranged at such angles that 100 the cables 25 will meet at a common point 29, while the cables 24 will meet at a corresponding common point 30, at which points the cables 31 and 32 are attached to the ends of the said cables 24 and 25. These cables 105 31 and 32 pass over the pulleys 33 and 34, respectively, journaled upon the derrick arm 35, from whence they pass to the drum 36, upon which they are oppositely wound. The drum 36 is keyed to the supporting 110 drive shaft 37, journaled in the brackets 38 carried by a support 39.

The operation of the device is as follows: As the drum 36 is rotated, through any suitable source of power, in the direction of the arrow, shown in Fig. 2^a, tension will be exerted upon the cables 24, which draws the rods 22 and 23 inwardly and, consequently, the pointed terminals 18 of the prongs 17 into engagement with the object to be lifted. The derrick arm 35 can then be swung in any preferred manner to deposit the article engaged by the prongs 17, at the desired locality. The drum 36 can then be rotated in a reverse direction which draws the rods 22 and 23 outwardly through the medium of the cables 25, consequently moving the prongs 17 outwardly, releasing the article engaged thereby, and permitting the grappling hook 5 to be again used as previously described.

20 It should be understood in this connection that various minor changes in the specific details of construction can be resorted to within the scope of the appended claims without departing from or sacrificing any of the advantages of the invention.

What is claimed is:

1. In a grappling hook such as described, a plurality of supporting members, slides movable upon the supporting members, prongs carried by the slides and movable therewith to and from each other, rods connecting certain of said prongs, and means engaging said rods for forcing the prongs and slides to and from each other.

35 2. In a grappling hook such as described, a plurality of supporting members, U-shaped slides movable upon said supporting members, prongs carried by the slides, bars connecting certain of said prongs, and means for moving said bars to and from each other and moving the prongs to engage or disengage an article to be lifted.

40 3. In a grappling hook such as described, end bars, supporting bars connecting said end bars, U-shaped slides upon the supporting bars, means for movably attaching said slides to the supporting bars, grappling prongs carried by the slides, rods connecting certain of said grappling prongs, and means for operating the rods to move the grappling prongs to and from each other.

45 4. In a grappling hook such as described, a pair of spaced end bars, supporting bars connecting said end bars, U-shaped slides movable upon said supporting bars, shanks connected to said U-shaped slides, grappling prongs carried by said shanks, said grappling prongs being disposed at the opposite ends of the grappling hook, said prongs at 55 the opposite ends of the grappling hook

being curved inwardly, rods connecting the prongs at each end of said grappling hook, and oppositely extending cables attached to said rods, whereby the prongs can be moved to and from each other.

65

5. In a grappling hook such as described, a pair of end bars, supporting bars connecting said end bars, U-shaped slides located upon the supporting bars, shanks engaging the U-shaped slides, prongs formed upon 70 said shanks, plates engaging said slides upon opposite sides of the supporting bars, U-bolts surrounding the shanks and U-shaped slides, and connected to the plates, the prongs upon opposite ends of the grappling hook being curved inwardly, rods connecting the prongs at each end of the grappling hook, cables attached to said rods, certain of said cables extending inwardly and the remainder of the cables extending outwardly, said inwardly extending cables being united, and said outwardly extending cables being united, and operating cables attached to the united ends of the before-mentioned cables.

80

6. In a grappling hook such as described, a pair of channeled end members, supporting bars engaging said end members, brackets rigidly connecting the supporting bars and end members, intermediate bars 90 connecting said end members, pulleys journaled in said intermediate bars, pulleys mounted upon said end members, U-shaped members slidably upon the supporting bars, shanks engaging the U-shaped members, 95 plates engaging the U-shaped members upon opposite sides of the supporting bars, U-bolts connecting the shanks, U-shaped slides and plates slidably upon the supporting members, inwardly curved prongs formed 100 upon the shanks, said prongs at opposite ends of the grappling hook being curved inwardly, rods connecting the prongs at the opposite ends of the grappling hook, inwardly extending cables connected to said 105 rods and passing over the inner pulleys, outwardly extending cables connected to said rods and passing over the outer pulleys, said inwardly extending cables being united and said outwardly extending cables being 110 united, a rotatable drum, and cables wound in opposite directions upon said drum and connected to the united ends of the first-mentioned cables.

110

In testimony whereof I have affixed my 115 signature in presence of two witnesses.

FRANK N. CANULETTE.
